RESILIENTLY MOUNTED SLUNG SEAT
CHAIR

Benjamin Bloom, Brooklyn, N. Y.

Application April 7, 1950, Serial No. 154,571

8 Claims. (Cl. 155—54)

1

This invention relates to an article of furniture, and more particularly, to a chair of the type in which the seat structure is swingably suspended from a cantilever arm.

It is an object of the invention to provide a swingable seat in which the center of gravity of a person sitting in the chair will be below the point of support for the seat thus producing a very stable, yet swinging, rocker-like chair, and when the seat is at rest the center of gravity is always in the vertical plane of the hinge or hinge-pin permitting complete relaxation for the person.

Another object is to provide a chair, the base member of which and the arm and seat members of which are so arranged that added "softness" or comfort is provided for the user.

Still another object is to provide a chair of the above type of simple construction, which may be readily assembled so that the cost of manufacturing is greatly reduced.

For a fuller understanding of the nature and objects of the invention, reference is had to the following detailed description, in connection with the accompanying drawing, in which:

Fig. 1 is a perspective view of a chair with part of the fabric cut away.

Fig. 2 is an enlarged sectional view taken through line 2—2 of Fig. 1, showing one means of attaching the fabric to the tubing.

Fig. 3 is an enlarged sectional view taken through line 3—3 of Fig. 1, showing one means of attaching the base to the swingable seat.

Fig. 4 is a perspective view of a modified chair of the same type showing another means of attaching a fabric to the frame.

The illustrated embodiment of the invention comprises mainly two pieces, to wit a base or under frame and a swingable or slung seat. The base consists of a bent tube having a rear base portion 10 and side base portions 11, 12 bent forwardly at right angles from the rear portion 10 along the same horizontal plane. Integral with the side and rear base portions of the base and bent upwardly and rearwardly therefrom are leg portions 13, 14. Approximately at the center point of the side base portions 11, 12 and integral with the leg portions and bent upwardly and vertically are end portions or side arms 15, 16. The upper hollow end of the end portions 15, 16 may be internally threaded and plugged with an externally threaded terminal 17 having a projecting plate 18 integral therewith, as shown in Fig. 3. Plate 18 has a transverse hole therethrough.

The swingable or slung seat consists of bent 55 uniformly spaced apart permitting the fabric 131

2

tubing having a front portion 19 and side portions 20, 21 bent rearwardly at right angles to the front portion and along the same horizontal plane. Integral with the side portions of the seat and bent upwardly at approximately right angles therefrom are rear portions 22, 23 and bent forwardly from the rear portions are cantilever arm portions 24, 25 with downwardly and angularly bent front ends 26, 27.

10 Approximately in the center of each of the arm portions 24, 25 and depending therefrom is an inverted U-shaped plate 28, as shown in Fig. 3, which may be brazed onto the arms 24, 25 or attached by any other well known means. 15 Plate 28 has a hole transversely through the arms thereof of the same size as the hole in plate 18 and the spacing therebetween is sufficiently wide to accommodate the plate 18 with a washer 29 and 30 on each side thereof. The opposed ends 20 of the hole of plate 28 are countersunk and a pin 31 is adapted to fill the holes of plates 18 and 28 and hold the base and seat together in swingable relation to each other.

25 A fabric 31, such as canvas, or any other desirable and well-known material may be attached between the side portions 20, 21 and the rear portions 22, 23 by any known means. In Fig. 2 there is shown one means for illustrative purposes only. This means consists of a slotted tubing, the slotted ends 32, 33 being bent inwardly leaving rounded opposed edges 34, 35. The slotted tubing provides resiliency between the opposed sides of the tubing which permits the edges of the fabric 31 to be wedged between the rounded edges 34, 35 by a series of wedges 36 or a continuous wedge, thus retaining the fabric 31 firmly between the side and rear portions, 20, 21, 22, 23, respectively. The front edge of the fabric 31 is wedged to the front portion 19 in the same manner.

30 In Fig. 4 another means of attaching a fabric by lacing will be hereinafter described.

35 In Fig. 4, there is shown a modification of the chair shown in Fig. 1. It is the same in all respects except that the tubing 122, 123 is bent upwardly at an angle greater than a right angle to the side portions 120, 121 and is higher and bent again downwardly upon itself providing back portions 137, 138. The cantilever arm portions 124, 125 are integral with the back portions 137, 138 and are otherwise formed like arm portions 24, 25. The fabric 131 has a series of eyelets 139 adjacent the fabric edge and the tubing 119, 120, 121, 122, 123 has a series of holes 140

to be laced to the tubing by lacing 141, as shown.

It is further obvious that instead of the pin 37 and plates 18, 28 a freely rotating connection, such as a ball and socket joint may be used, or any other known means.

Various changes and modifications may be made in the details of construction and arrangement of parts without departing from the general spirit of the invention, such as the substitution of plywood instead of tubing bent substantially in the form of the tubing shown, or certain types of plastic material or other similar material. Also, the tubing 122, 123 in Fig. 4 need not be bent downward upon itself to form back portions 137, 138. The rear ends of the cantilever arms may be brazed or otherwise joined approximately in the center of the tubing 137, 138.

I claim:

1. In an article of furniture, a base and a swingable seat structure, said base consisting of bent tubing with two opposed side arms bent upwardly approximately over the center of said base, said seat structure having two opposed cantilever arms, said seat structure being swingably supported by said cantilever arms which are pivotally connected to said opposed side arms of said base, said base and seat structure each bent from a single piece of tubing.

2. In an article of furniture, a base and a swingable seat, said base consisting of a single piece of bent tubing a portion of which forms a ground engaging portion and another portion comprising two opposed side arms, said side arms bent upwardly approximately over the center of said base, said seat consisting of a single piece of bent tubing with fabric therebetween, said seat having a back frame and two opposed cantilever arms integral with said seat and back frame, said cantilever arms bent forwardly from said back frame, said seat swingably supported by said cantilever arms which are pivotally connected to said opposed side arms of said base.

3. In an article of furniture, a base and a swingable seat, said base consisting of a single piece of bent tubing having a rear base portion, opposed side base portions bent forwardly at approximately right angles to said rear portion forming a ground engaging portion, opposed leg portions, said leg portions bent upwardly and rearwardly from said side base portions, opposed end portions integral with said leg portions, said end portions bent upwardly vertically from said leg portions approximately at the center of said side base portions, said seat consisting of a single piece of bent tubing having a front portion and opposed side portions bent rearwardly at right angles to said front portion on the same horizontal plane, opposed rear portions integral with said side portions, said rear portions bent upwardly from said side portions, and at right angles to said side portions opposed cantilever arms integral with said rear portions and bent forwardly from said rear portions, said seat swingably supported by said cantilever arms pivotally connected to said end portions of said base permitting said seat to swing freely on said base.

4. In an article of furniture, a base and a swingable seat, said base consisting of a single piece of bent tubing having a rear base portion, opposed side base portions bent forwardly at approximately right angles to said rear portion on the same horizontal plane, forming a ground engaging portion, opposed leg portions integral with said side and rear base portions, said leg portions

bent upwardly and rearwardly from said side base portions, opposed end portions integral with said leg portions, said end portions bent upwardly vertically from said leg portions approximately at the center of said side base portions, said seat consisting of a single piece of bent tubing having a front portion and opposed side portions bent rearwardly at right angles to said front portion on the same horizontal plane, opposed rear portions integral with said side portions, said rear portions bent upwardly from said side portions and at right angles thereto, material attached to said front, side and rear portions forming a support for a person, opposed cantilever arms integral with said rear portions and bent forwardly from said rear portions, said seat swingably supported by said cantilever arms pivotally connected to said end portions of said base permitting said seat to swing freely with the center of gravity of the seated person below the support of said seat.

5. In an article of furniture, a base and a swingable seat, said base consisting of bent tubing having a rear base portion, opposed side base portions bent forwardly at approximately right angles to said rear portion on the same horizontal plane forming a ground engaging portion, opposed leg portions integral with said side and rear base portions, said leg portions bent upwardly and rearwardly, opposed end portions integral with said leg portions, said end portions bent upwardly vertically approximately at the center of said side base portions, said seat consisting of bent tubing having a front portion and opposed side portions bent rearwardly at right angles to said front portion on the same horizontal plane, opposed rear portions integral with said side portions, said rear portions bent upwardly from said side portions at an angle greater than 90° to said side portions, said rear portions extending above said base and bent downwardly upon themselves forming a back rest, material attached to said front, side and rear portions forming a support for a person, opposed cantilever arms integral with said rear portions and bent forwardly from said rear portions, said seat swingably supported by said cantilever arms which are pivotally connected to said end portions of said base permitting said seat to swing freely on said base.

6. In an article of furniture, a base and a swingable seat, said base consisting of a single piece of bent material having a rear base portion, opposed side base portions bent forwardly at approximately right angles to said rear portion on the same horizontal plane forming a ground-engaging portion, opposed leg portions integral with said side and rear base portions, said leg portions bent upwardly and rearwardly from said side base portions, opposed end portions integral with said leg portions, said end portions bent upwardly vertically from said leg portions approximately at the center of said side base portions, said seat consisting of a single piece of bent material having a front portion and opposed side portions bent rearwardly at right angles to said front portion on the same horizontal plane, opposed rear portions integral with said side portions, said rear portions bent upwardly from said side portions at an angle greater than 90° to said side portions, said rear portions extending higher than said base forming a backrest, material attached to said front, side and rear portions forming a support for a person, opposed cantilever arms substantially

parallel to said side portions and joined approximately at the center of said rear portions, said seat swingably supported by said cantilever arms pivotally connected to said end portions of said base, permitting said seat to swing freely of said base.

7. A chair having an under frame bent from a single piece of tubing, said under frame having two spaced side frames, said under frame comprising means forming a ground engaging portion, said side frames bent rearwardly approximately to the center of the side of said ground engaging portion, a seat and seat back frame having two cantilever arms, said seat back frame and cantilever arms bent from a single piece of tubing and suspended by said cantilever arms, connecting means on said cantilever arms and said side frames permitting said seat to swing freely on said under frame.

8. In an article of furniture, a supporting base

and a seat structure, said seat structure bent from a single piece of tubing and swingably suspended by two spaced cantilever arms integral with the tubing of said seat structure, said base having two spaced side frames, said cantilever arms pivotally connected to said supporting base to permit said seat structure to swing freely, said base and said side frames bent from a single piece of tubing.
